No. 12.175

FEB 15, 1881

UNITED STATES PATENT OFFICE.

GARRETTSON SMITH, OF PHILADELPHIA, ASSIGNOR TO OLIVER B. KEELEY,
OF SPRING CITY, PENNSYLVANIA.

DESIGN FOR A COOKING-RANGE.

SPECIFICATION forming part of Design No. 12,175, dated February 15, 1881.

Application filed January 18, 1881. Term of patent 7 years.

To all whom it may concern:

Be it known that I, GARRETTSON SMITH, a citizen of the United States, residing in Philadelphia, Pennsylvania, have invented or produced a new and original Design for a Cooking-Range, of which the following is a specification.

My design is fully shown in the accompanying drawing, which represents a perspective view of the range.

The range has a flat top, A, and flat hearth-plates B and D, each having a beveled and polished edge, a.

The main oven-door is rectangular in shape, and has two rows of beveled beading, b and d, and an ornamental border, e, surrounding the central panel, f, which carries the title of the stove and has a fluted edge.

The front fire-door has a beveled edge, g, ornamental border h, and two mica panels, i i, the end fire-door having a beveled edge, g', border h', and four mica-panels, i'.

The front ash-door has a central damper, m, and an ornament, n, on each side thereof.

The feet s are shaped as shown, and have 25 face ornaments t and u.

I claim—

1. The design for the oven-door, said design comprising the beveled beads b d, the border e, and the central panel, f, as shown and described. 30

2. The design for the complete range, said design comprising the top and hearth plates, with beveled edges, the oven-door, front and end fire-doors, ash-pit door, and feet, as shown and described. 35

In testimony whereof I have signed my name to this specification in the presence of two subscribing witnesses.

GARRETTSON SMITH.

Witnesses:

EMELINE JONES,
HARRY SMITH.
